America as represented by the Secretary of the
Navy

Application October 11, 1945, Serial No. 621,836

7 Claims. (Cl. 315—24)

1

The present invention relates to radio echo detection apparatus and more particularly to a circuit for providing a radial sweep on the cathode ray tube indicator thereof, so as to cause the same to furnish a presentation characterizing the cathode ray tube indicator as a "Plan Position Indicator."

One such circuit is disclosed in copending application Serial 594,044, filed May 16, 1945 for Radio Echo Detection System by James F. Koehler. In that circuit the radial and rotating sweep by the electron beam of the cathode ray tube indicator is provided by varying the amplitude of a sawtooth wave voltage, sinusoidally in two parts 90° out of phase by means of a rotary two-phase transformer.

An object of the present invention is to provide a circuit corresponding to that disclosed in the aforesaid patent application, wherein the sinusoidal variations in the amplitude of a sawtooth wave voltage are obtained by applying it to a three-phase rotary transformer.

This and other objects will be apparent from the following specification when taken with the accompanying drawing comprising a circuit diagram disclosing the invention.

In the drawing, a rotary three-phase transformer 1 is provided with a rotatable primary winding 2 and secondary windings 3, 4, and 5. One end of the primary winding 2 is connected to a suitable source of voltage having a sawtooth wave form 6. The sawtooth wave voltage is generated in any suitable manner such as disclosed in the aforesaid copending application. Also the leading edge of the sawtooth voltage wave form 6 may be provided with a pip 7 by some suitable means such as disclosed in said application to charge capacities existing in the leads to the winding 2 and in the winding 2 itself. The other end of the winding 2 is connected to a suitable source 8 of positive potential.

The secondary windings 3, 4 and 5 are connected in Y formation as indicated, and the arrangement is such that the windings produce maximum voltages at 120° spacing of the rotary winding 2. The ends of the secondary windings 3, 4 and 5 are connected to three resistors 10, 11 and 12 respectively, also connected together in Y formation. A point 13 of the resistor 12 is connected to ground, this point being selected so as to make the ends of the resistors 10 and 11 90° apart electrically instead of 120°. The voltages produced at the outer ends of the resistors 10 and 11 are used to control the deflection plates

2

of the cathode ray tube indicator hereinafter described.

The voltages at the outer ends of the resistors 10 and 11 cannot be connected directly to the opposed deflection plates respectively of the hereinafter described cathode ray tube indicator for a push-pull operation since they are single-ended outputs. To overcome this difficulty a circuit comprising electron tubes 14 and 15 is provided. The electron tube 14 is provided with a cathode 16, control grid 17 and anode 18 while the tube 15 is provided with a cathode 19, a control grid 20 and an anode 21. The voltage at the outer end of the resistor 10 being in the form of a sawtooth wave having a sinusoidally varying amplitude is connected to the control grid 17 of the electron tube 14. The grid 17 is connected to ground through resistors 24 and 25. The juncture of the resistors 24 and 25 is connected to ground through a capacitor 26. The same juncture is also connected to the movable arm 27 of the potentiometer 28. One end of the potentiometer 28 is connected to a positive source of voltage 29 and the other end of the potentiometer 28 is connected to ground.

The cathode 16 of the tube 14 is connected to ground through a resistor 30, and the anode 18 is connected to a source 31 of positive potential through a load resistor 32. The anode 18 is also connected to the control grid 34 of a power beam amplifying tube 35 the output of which is connected to a deflection plate 36 of a cathode ray tube indicator 37.

The control grid 20 of the electron tube 15 is connected to ground while the cathode 19 thereof is connected to the cathode 16 of the tube 14. The anode of the tube 15 is connected to a source 38 of a positive potential through a suitable load resistor 39. The anode 21 is connected to the control grid 40 of a power beam amplifier 41 the output of which is connected to a deflection plate 42 opposite the deflection plate 36 of the cathode ray tube indicator 37. Thus the two anodes 18 and 21 furnish the deflecting voltages for the vertical deflecting plates 36 and 42 of the cathode ray tube indicator 37.

In order for the circuit to operate as desired the characteristics of the tubes 14 and 15 should be substantially the same and the resistors 32 and 39 substantially equal in value. Also the value of the resistor 30 should be such that when multiplied by the amplification factor of one of the tubes 14 or 15 the product will be much 55 greater than the sum of the plate resistance of

one of the tubes plus the load resistance of that tube.

The horizontal deflection plates 50 and 51 of the cathode ray tube indicator 37 are connected respectively to anodes 52 and 53 of power beam amplifying tubes 54 and 55. The screen grids of the tubes 52, 53, 41 and 35 are connected together and to a source 56 of positive potential. The cathodes of the tubes 54, 55, 41 and 35 are connected respectively through resistances 57, 58, 59 and 60 to a common lead 61 which is connected through a resistance 62 to ground. The anodes of the tubes 54, 55, 41 and 35 are connected through resistors 65, 66, 67 and 68 respectively to the source 56 of positive potential to provide operating potentials.

The phase inversion circuit disclosed in the upper portion of the drawing for furnishing push-pull potentials from the outer end of the resistor 10 for energizing the vertical deflecting plates 42 and 36 of the cathode ray indicator 37 is duplicated by a circuit, not shown, for energizing the horizontal deflecting plates 51 and 50 of the cathode ray tube indicator 37 from the output 69 at the end of the resistor 11.

In the operation of the circuits described above and shown in the drawings the sawtooth wave from the rotary transformer 1, as taken from the outer end of the resistor 10, is applied to the grid 17 of the tube 14. The potentiometer 28 is adjusted so that current will normally flow in both tubes 14 and 15. The current in the tube 14 will then increase as the voltage of the sawtooth wave rises. Since no voltage is applied to the grid 20 of the tube 15, this tube would normally not be affected by the signal. However, the two cathodes 16 and 19 are connected together and through the resistor 30 to ground, and therefore the current flowing in the tube 14 passes through the resistor 30 and raises the potential of the cathode 16 because of the voltage drop through the resistor 30. This also raises the potential of the cathode 19 which therefore becomes less negative with respect to the grid 20 in proportion to the signal applied on the grid 17 of the tube 14. The potential on the cathodes 16 and 19 corresponds to about one-half of the signal potential. This causes the potential of the anode 18 of the tube 14 as the current increases in that tube, to swing in a negative direction through an amount proportional to one-half of the signal applied to the grid while the potential of the anode 21 of the tube 15 will swing in a positive direction through substantially the same amount as the current is reduced in that tube due to the increase in voltage of the cathode 19 thereof. Thus, sawtooth voltage waves opposite in phase appear on the anodes 18 and 21 of the tubes 14 and 15 respectively and thus may be applied to the amplifiers 41 and 35 respectively feeding the vertical deflecting plates 42 and 36 of the cathode ray indicator tube 37. The signals from these tubes 14 and 15 will be equal in amplitude but opposite in phase and the amplitude will vary sinusoidally as the rotary primary 2 of the rotary transformer 1 rotates.

The sinusoidal variation of the push-pull sawtooth voltages obtained from the output 69 of the resistor 11 will be 90° out of phase with the sinusoidal variation taken from the outer end of the resistor 10 due to the grounding of the point 13 of the resistor 12. Thus, the sweep produced on the cathode ray tube indicator 37 will rotate about a point to provide a plan position indicator.

It is not necessary to produce a deflection of

the electron beam of the cathode ray tube indicator 37 by applying deflection voltages in push-pull arrangement. A sawtooth voltage sufficient to deflect the electron beam may be applied to one horizontal and one vertical electrode deflection plate, the others being kept at constant voltages. In such a case, however, the difference between the maximum voltage applied to the plate and the other elements of the cathode ray tube is much greater than the case where the deflection voltages are applied to the deflection plates in push-pull. There may be a tendency for these high voltage differences to interfere with the functioning of the electron beam and hence I prefer to use the push-pull arrangement. While I have not shown a clamping arrangement for starting each electron beam sweep from the same point on the indicator 37, it is to be understood that such an arrangement, for example, as disclosed in aforesaid patent application, may be used.

Having thus described my invention what I desire to secure by Letters Patent and claim is.

1. In a radio echo detection system a circuit for producing a plan position indicator scan comprising a three-phase rotary transformer having a rotating primary winding and three Y connected secondary windings, three Y connected resistors, conductors connecting the outer end of said resistors to the outer end of said secondary windings respectively, means for grounding an intermediate portion of one of said resistors so as to provide the output voltages from the other of said two resistors 90° electrically out of phase, means to split the output from at least one of said last-named resistors into two parts 180° out of phase, a cathode ray tube indicator having opposing deflection plates, and means to apply said out of phase output in push-pull to opposing deflection plates of said cathode ray tube indicator.

2. A circuit for providing a plan position indicator sweep on a cathode ray tube indicator comprising means for furnishing a sawtooth wave form voltage, a rotary transformer for sinusoidally varying the amplitude of said saw-tooth voltage, means for providing two 90° out of phase voltages from said transformer, means to divide each of said last-named voltages into two 180° apart voltages and means for applying one set of said 180° apart voltages to the horizontal deflecting plates of a cathode ray indicator and the other set of 180° apart voltages to the vertical deflecting plates of a cathode ray tube indicator.

3. In a circuit of the character described a three-phase rotary transformer having a rotary primary winding and three Y connective secondary windings, three Y connective resistors one corresponding to each of said secondary windings, conductors connecting the ends of said windings and resistors respectively, a ground connection at an intermediate point of one of said resistors to provide a predetermined phase difference in the voltages at the outer end of the other two of said resistors, a cathode ray indicator, and means for applying said voltages to said indicator to deflect the electron beam thereof.

4. In a radio echo detection system, a circuit for producing a plan position indicator scan comprising a substantially symmetrical three-phase rotary transformer, two output circuits from said transformer, means to reduce the normal phase difference between said outputs to provide driving circuits 90° apart, means to split the phase of said driving circuits respectively to produce push-pull outputs, a cathode ray tube indicator, and

means to apply said push-pull outputs to said indicator to cause a sweeping by the electron beam thereof.

5. In a radio echo detection system, a circuit for producing a plan position indicator scan comprising, a source of sawtooth wave form voltage, a three-phase rotary transformer having a rotary primary winding and three Y-connected secondary windings, three Y-connected resistors, one corresponding to each of said secondary windings, conductors connecting the ends of said windings and resistors respectively, means for energizing the rotary primary of said transformer from said source, a ground connection at an intermediate point on one of said resistors to provide a predetermined phase difference in the voltages at the outer end of the other two of said resistors, a cathode ray indicator, and means for applying said last-mentioned voltages to said indicator to deflect the electron beam thereof.

6. A circuit for providing a plan position indicator sweep on a cathode ray indicator comprising, a source of a sawtooth wave form voltage, a three-phase rotary transformer having a rotating primary winding and three Y-connected secondary windings, means for energizing said primary winding from said source, three Y-connected resistors, conductors connecting the output end of said resistors to the outer end of said secondary windings respectively, means for grounding an intermediate portion of one of said resistors so as to provide the output voltages from the other of said two resistors 90° electrically out of phase, means to divide each of said last-named voltages into two voltages 180° out of phase, a cathode ray indicator having opposing deflection plates, and means for applying one set

of said 180° apart voltages to the horizontal deflecting plates of said indicator and the other set of 180° apart voltages to the vertical deflecting plates of a cathode ray indicator.

7. A circuit for providing a plan position indicator sweep on a cathode ray indicator comprising, a source of a sawtooth wave form voltage, a three-phase rotary transformer having a rotating primary winding, and three Y-connected secondary windings, means for energizing said primary winding from said source, three Y-connected resistors, conductors connecting the outer end of said resistors to the outer end of said secondary windings, respectively, means for grounding an intermediate portion of one of said resistors so as to provide the output voltages from the other of said two resistors 90° electrically out of phase, an electron tube phase inverting circuit responsive to each of said last-named voltages to obtain two sets of voltages, each having a pair of voltages differing in phase by 180° and means for applying one set of said 180° apart voltages to the horizontal deflecting plates of said indicator and the other set of 180° apart voltages to the vertical deflecting plates of said indicator.
